UNITED STATES PATENT OFFICE.

SAMUEL R. FRAIM, OF LANCASTER, PENNSYLVANIA, ASSIGNOR TO THE E. T. FRAIM
LOCK COMPANY, A CORPORATION OF PENNSYLVANIA.

LOCK-CASE.

1,253,677.

Specification of Letters Patent. Patented Jan. 15, 1918.

Application filed May 1, 1916. Serial No. 94,818.

To all whom it may concern:

Be it known that I, SAMUEL R. FRAIM, a citizen of the United States, residing at Lancaster, in the county of Lancaster and 5 State of Pennsylvania, have invented certain new and useful Improvements in Lock-Cases, of which the following is a specification.

This invention relates to lock cases, the 10 novel features of construction involved being herein shown as incorporated in a padlock but as will be clear from an understanding of the invention they may with 15 advantage be applied to the cases of other forms of locks.

The primary object which I have in view 20 is to provide a lock case which while providing a strong, tight closure for the lock shall also provide simple easily applied means for maintaining the working parts of 25 the lock in place and shall be of cheap manufacture and easy of assembling.

With this object in view the invention 30 consists of a lock case in which are combined the generic and specific features of construction and arrangement of the parts substantially as hereinafter described and claimed.

In Figures 1 to 3, I have shown the preferred construction of the case. In this 35 drawing;

Fig. 1 is a side elevation of a complete lock made in accordance with my invention.

Fig. 2 is a perspective view of the body of the lock;

Fig. 3 is a vertical sectional view of a 40 complete lock.

In this drawing 1 represents the body of the lock which is substantially circular in general contour having at one side offset 45 angular shoulders 2 with openings 3 therein for the reception of the ends of the shackle 4 which latter is herein shown as of the sliding type. The side of the body 1 opposite to that at which the shoulders 2 are placed 50 is provided with a key opening 5, the opening being circular in form and having arranged therein a rotatable disk 6, slotted through the center for the reception of a key.

55 The body 1 has formed in it a chamber which is as herein shown preferably circular in form in order to permit the outer edges

of the walls thereof to be turned inward by spinning. Arranged within the chamber are two disks 7 to which are attached the 55 interior movable operative portions of the lock.

The disks 7 are each in a completed lock located a short distance from an outer edge of the body, and outside of these disks are 60 arranged the face plates 8 of the lock.

In assembling the lock, the disks 7 between and to which the parts for locking the shackle and for projecting the latter from the case when released are attached, 65 are introduced into the body, and the disks are secured together. After one of the face plates is introduced into the circular chamber of the body just inside the outer edge of the latter, the outer edge is turned inward over the outer edge of the face plate 70 by spinning or in any other suitable way. The second face plate is secured in place in the same way as the first, and thus a complete substantially water-tight closure is 75 effected with a minimum amount of labor, adjustment and manipulation, and the working parts are held in place.

The face plates preferably though not necessarily bear against some portions of the 80 interior disks in order to hold them in place while being attached to the body in the manner described.

I claim;

A lock case comprising a substantially 85 annular body member having a circular opening through the same forming a chamber, two disks arranged within the opening and respectively located adjacent to the opposite edges of the body member, oppositely 90 arranged face plates located within the circular opening and bearing on the adjacent disks, an annular flange on both edges of said body member projecting beyond the 95 face plates adapted to be turned over the edges of the face plates to close the body member over said plates and secure the interior parts of the lock in place.

In testimony whereof I affix my signature in the presence of two witnesses.

SAMUEL R. FRAIM.
